(57) **CLAIM**

The ornamental design for an elevated pet feeder, as shown and described.

DESCRIPTION

FIG. 1 is a perspective view of the elevated pet feeder according to the present disclosure;

FIG. 2 is a front side view of the elevated pet feeder according to the present disclosure;

FIG. 3 is a back side view of the elevated pet feeder according to the present disclosure;

FIG. 4 is a left side view of the elevated pet feeder according to the present disclosure;

FIG. 5 is a right side view of the elevated pet feeder according to the present disclosure;

FIG. 6 is a top view of the elevated pet feeder according to the present disclosure; and,

FIG. 7 is a bottom view of the elevated pet feeder according to the present disclosure.

The broken lines illustrate portions of the elevated pet feeder that form no part of the claimed design.

1 Claim, 6 Drawing Sheets
